UNITED STATES PATENT OFFICE.

NORBERT SCHREIBER, OF LINCOLN, ILLINOIS, ASSIGNOR TO AMERICAN STEAM BOILER
CLEANER CO., OF SAN ANTONIO, TEXAS, A CORPORATION OF TEXAS.

BOILER-SKIMMER.

1,304,385.

Specification of Letters Patent.

Patented May 20, 1919.

Application filed June 21, 1916. Serial No. 104,997.

To all whom it may concern:

Be it known that I, NORBERT SCHREIBER, a citizen of the United States, residing at Lincoln, in the county of Logan and State of Illinois, have invented a certain new and useful Improvement in Boiler-Skimmers, of which the following is a full, clear, concise, and exact description, reference being had to the accompanying drawings, forming a part of this specification.

My invention relates to boiler skimmers.

Prominent objects of the invention are to provide a practical and effective construction of boiler skimmer; to arrange for the easy adjustment of the skimmer with reference to the varying level of the water; to prevent the collapse of the floats on the skimmer by external pressure, as for example high pressure of steam in the locomotive boiler; to provide for holding the floats securely in position; and to secure the foregoing and other desirable results in a simple and expeditious manner.

In the accompanying drawings Figure 1 is a longitudinal section of a portion of a locomotive boiler provided with a boiler skimmer embodying my invention;

Fig. 2 is a plan view of the skimmer;

Fig. 3 is an end elevation of the same;

Fig. 4 is an elevation partly in section of a float for the skimmer; and

Fig. 5 is a cross section taken on line 5—5 in Fig. 4.

Referring to Fig. 1, the top of the locomotive boiler is indicated at 1 and the steam dome of said boiler at 2. A dry pipe 3 is shown within the boiler and steam dome 2. The boiler skimmer shown within the boiler has an elevated pipe or member 4 which extends lengthwise of the dry pipe 3 above the same. A pipe connection 5 extends upwardly from the pipe 4 to the boiler top 1 opening through the same, being provided with a valve 6 and controlling handle 7. By

this connection the skimmer may be drained or discharged outside of the boiler and at the same time the pipe 4 with its attached elements may be mounted upon or attached to the boiler. Cross pipes 8 and 9 extend laterally from the opposite ends of the central elevated pipe 4 and side pipes 10 and 11 extend down from the opposite ends of these pipes 8 and 9. These vertically arranged side pipes 10 and 11 are fairly close to the

dry pipe 3, as shown in Fig. 3 whereby these pipes with the cross pipes 8 and 9 form a saddle for the dry pipe permitting the skimmer to straddle the dry pipe, but holding the skimmer in proper central relative position. Other side pipes 14 and 15 are arranged on the outer sides of the side pipes 8 and 9, respectively and extend downwardly alongside of the same. At the lower ends of the pipes 14 swinging pipes 16 are pivoted, these pipes 16 being capable of swinging vertically about their pivotal connections 17 at the lower end of said pipes 14. In a similar way other pipes 18 are pivoted at 19 to the lower ends of the side pipes 15. Between the upper or swinging ends of the pipes 16 and 18 other pipes 20 are extended, these pipes 20 being pivoted at 21 and 22, respectively, to the upper ends of the pipes 16 and 18. Thus on each side of the skimmer there is provided a jointed frame consisting of the two swinging end pipes 16 and 18 and the connecting horizontal pipe 20, the latter being provided with intake apertures 24, through which the scum and dirt on the surface of the water may escape. Floats 25 are mounted upon these jointed frames, said floats being preferably secured to the side pipes 20 at or near the ends thereof and also at points between the ends, as shown in Figs. 1 and 2. These floats 25 are preferably made of two cylindrical halves welded together, so as to be as near non-collapsible as possible.

Counterbalancing rods 27 are secured at 28 to the swinging members 18, said rods 27 being provided with counterweights 30 by which said side jointed frames are substantially counterbalanced. In this way the weight of said jointed frames is pretty well taken up so that said frames are very sensitive and adjust themselves very quickly and accurately to changes in the water level of the boiler.

As a matter of further and specific improvement the floats 25 are secured to the skimmer by means of clamps 31, which clamps are best shown in Figs. 4 and 5. Each clamp consists of a tubular portion 32 adapted to fit over the pipe 20 or other suitable member, said tubular portion 32 being clamped together by means of bolts 33 so as to grip firmly the pipe or member 20. Another bolt 34 is passed through the tubular

member 32 so as to engage and bite directly the member 20. Annular bands or rings 35 extend around the float 25 and are held firmly together at their split ends by bolts 36 whereby said bands may be drawn tightly around said floats. The bands 35 are secured to the body member 37 which connects the tubular member 32 with said bands 35. The body member 37 is preferably provided 10 with a recess portion to receive an annular projection or flange 38 (Fig. 4) upon the float 25, thus insuring a tight fit between the clamp and float.

As a matter of still further improvement 15 the floats 25 are preferably provided with apertures by which compressed air or other fluid under pressure may be introduced within them, this internal pressure being provided in order to counteract to a greater or less degree the external pressure due to the steam pressure inside of the boiler. As one arrangement I show an aperture at the end of the float 25 (Fig. 4), said aperture being shown closed by a plug 40 which may 20 have a threaded connection with the interior of the aperture. In this way air or other fluid under pressure may be introduced and then the aperture closed by the plug so as to retain the internal pressure in the float. 25 By the use of this counteracting influence or agent, a further preventative of the collapse of the float is employed.

In using the skimmer, the pipe 4 with its attached members will form a stationary 35 frame which is attached or secured to the boiler 1 by means of the connection 5, this stationary frame fitting and being held close to the dry pipe 3. The jointed side frames comprising the arms 16 and 18 and connected parts, form movable frames with the skimming pipes or elements and these movable frames are movable relatively to the fixed frame just referred to, so that these adjustable frames adjust the skimming 40 elements quickly and accurately to changes in the water level in the boiler, this movement being assisted by means of the counter-balancing construction. The refuse matter skinned from the water is conveyed through 45 the various pipes and discharged through the pipe connection 5 to the exterior of the boiler. The valves 6 controlling this discharge is understood to be connected by a suitable connection 41 with the throttle 50 valve of the locomotive so that the discharge of the skimmer will be automatically brought about by the actuation of the throttle valve. The throttle valve and further connections are not shown herein as 55 they are fully disclosed and claimed in Letters Patent No. 1,165,717, issued December 28, 1915 to Raphael Rosenthal and myself.

It will be understood that changes and modifications may be made without departing 60 from the spirit of the invention.

What I claim is:

1. A device of the class specified comprising a stationary frame provided with a horizontally arranged pipe having its opposite ends provided with laterally extending horizontal cross pipes, a movable frame consisting of a pair of pipes extending longitudinally of said horizontally arranged pipe and provided with skimming apertures and floats and connections between said frames consisting of pipe members extending between the opposite ends of said skimming pipes and the ends of said cross pipes and pivotally connected with the same. 70

2. The combination of a jointed frame comprising a tubular member provided with intake openings and a pivoted member pivotally mounted at one end and pivotally connected with said tubular member at its other end, and a weighted counterbalancing 80 rod connected with said pivoted member between the ends thereof and extended to the side of said pivot on which said member is mounted opposite the pivotal connection between said tubular member and pivoted member. 85

3. A device of the class specified comprising a frame adapted to fit over the dry pipe of a locomotive boiler, said frame having downwardly extending legs arranged to fit on opposite sides of the dry pipe, said frame also having other downwardly extending members, and a jointed frame pivotally connected with the lower ends of said other 95 downwardly extending members. 100

4. In boiler skimming apparatus, the combination with a long fixed supporting pipe connected with the exterior of the boiler, parallel transversely extending pipe arms secured to the ends of said supporting 105 pipe and communicating therewith, an intake pipe coupled to the ends of said arms to swing bodily and having scum inlet openings, and floats on said intake pipe to keep it at the water surface and its inlet openings in position to receive scum, foam or other impurities to be removed. 110

5. In boiler skimming apparatus, the combination with a long fixed supporting pipe connected with the exterior of the 115 boiler, a long intake pipe, flexible piping connecting the ends of said intake pipe with the ends of the supporting pipe to permit the former to oscillate at each end about an axis at right angles to the latter, said 120 intake pipe having scum inlet openings, and floats on said intake pipe for keeping said pipe at the water surface with its inlet openings in position to receive scum, foam or other impurities to be removed. 125

6. In boiler skimming apparatus, the combination of a long fixed supporting pipe extending lengthwise of the boiler and connected with the exterior thereof, a long intake pipe having scum inlet openings, cou- 130

pling pipe arms connecting the ends of the intake pipe to the ends of the supporting pipe to permit bodily swing of said pipe, floats secured at intervals on said intake pipe, and a counterweight secured to one of said coupling pipes, said floats and counterweight coöperating to keep the intake pipe at the water surface with its inlet openings in position to receive scum, foam or 10 other impurities to be removed.

7. In boiler cleaning apparatus, the combination of a fixed supporting frame comprising a long longitudinal pipe and transverse pipes at the ends thereof, said pipes being interconnected and having valve controlled discharge outlets, an intake pipe at each side of said frame, flexible couplings connecting the ends of each intake pipe with the respective ends of the transverse pipes 15 whereby said intake pipes are independently bodily movable, each intake pipe having inlet openings, and float members secured to each intake pipe for holding said pipe at the water surface in order to keep its inlet openings at a level with the scum, foam or other 20 impurities to be removed.

8. In boiler skimming apparatus, the combination of a skimmer pipe, a supporting frame of piping having a valve controlled 30 outlet, pipe links coupled to said supporting frame and said skimmer pipe to adapt said pipe for vertical bodily movement, and float members independently supported from said skimmer pipe to be independently swung 35 bodily about the pipe axis into desired positions of adjustment.

9. In boiler skimming apparatus, the combination of a skimmer pipe, a supporting frame of piping having a valve controlled 40 outlet, pipe links coupled to said supporting frame and said skimmer pipe to adapt said pipe for vertical bodily movement, and float members independently supported from said skimmer pipe to be independently swung 45 bodily about the pipe axis into desired positions of adjustment, one of said links having a weight thereon for counter-acting the weight of said skimmer pipe and float members.

50 10. The combination with a boiler having a dry pipe extending longitudinally therethrough, a supporting frame fixed on said dry pipe and comprising a longitudinal pipe and transverse pipes at the end thereof, said 55 pipes being interconnected and having a valve controlled outlet, an intake pipe at each side of the dry pipe, coupling pipe arms connecting the ends of each intake pipe with the respective ends of the transverse pipes 60 of the supporting frame, said intake pipes having inlet openings, and floats on said intake pipes for keeping them at the surface of the water with their inlet openings in

position to receive scum, foam or other impurities. 65

11. In a boiler skimmer, tubular brackets, tubular connection establishing communication between the brackets, means for supporting the brackets in a boiler, tubular arms having swinging connection at one end with the lower ends of the brackets and disposed in parallel spaced relation, a skimmer pipe having swinging connection with the opposite ends of the arms, the arms having communication both with the pipe and with the 70 brackets and the pipe having inlet openings, closures for the ends of the pipe, floats carried by the pipe, and counterweights carried by the opposite ends of the arms whereby the floats and counterweights coöperate 75 to maintain the pipe with its inlet openings at substantially the level of water in the boiler while the arm connections between the pipe and brackets permit vertical movement of the pipe but hold it against angular 80 movement with respect to the brackets.

12. In a boiler skimmer, a pair of tubular substantially U-shaped brackets adapted to be rigidly secured within a boiler with their sides projecting downwardly, tubular connecting means between the brackets, a discharge leading from such connecting means, tubular arms having swinging and communicating connection one with each arm of each bracket, tubular skimmer elements connecting the free ends of the arms and communicating therewith and formed with inlet 90 openings, and floats carried by the skimmer 95 elements.

13. In a boiler skimmer, tubular brackets, 100 tubular connection establishing communication between the brackets, tubular arms having swinging connection at one end with the lower ends of the brackets, a skimmer pipe having swinging connection with the opposite ends of the arms, the arms having communication with both the pipe and the brackets, and the pipe having inlet openings, and floats carried by the skimmer pipe. 105

14. In a boiler skimmer, tubular brackets, 110 a tubular connection establishing communication between the brackets, tubular arms having swinging connection at one end with the lower ends of the brackets, a skimmer pipe having swinging connection with the opposite ends of the arms, the arms having communication with both the pipe and the brackets, the pipe having inlet openings, floats carried by the skimmer pipe, and counterweights carried by the arms. 115

In witness whereof, I hereunto subscribe my name this 29th day of May, A. D. 1916.

NORBERT SCHREIBER.
